Des. 186,666
Patented Nov. 17, 1959

186,666

IGNITION BREAKER ARM

Earl W. Meyer, Jr., Harry M. Seubert, and Robert J.
Latorre, Toledo, Ohio

Application June 12, 1958, Serial No. 51,320

Term of patent 14 years

(Cl. D26—13)

Fig. 1

Fig. 2

Fig. 3

Fig. 1 is a side elevational view of an ignition breaker arm, showing our new design, the opposite side being substantially a mirror image thereof;

Fig. 2 is a front elevational view; and

Fig. 3 is a rear elevational view thereof.

We claim:

The ornamental design for an ignition breaker arm, substantially as shown and described.
